OILING SYSTEM FOR LIFTS

William de Back, San Jose, Calif., assignor to
Food Machinery and Chemical Corporation, a
corporation of Delaware

Application October 21, 1946, Serial No. 704,772

8 Claims. (Cl. 184—6)

1

This invention relates to the lubrication art and more particularly to a self-contained oiling system suitable for automatically lubricating lifts of the type employed in the canning industry for presenting receptacles, such as cans or jars, to the filling valves of a filling machine.

The cans or jars handled by such machines are previously supplied with fruit or vegetables and are presented to the filling valves to receive a predetermined quantity of liquid, syrup, or the like. Consequently, with a view of attaining a greater degree of sanitation, the can lifting portions of such machines have been completely enclosed within protective skirtings whereby liquid or syrup spilling from the cans is prevented from contacting the moving parts of the machine and cleaning of the skirtings is facilitated without subjecting moving parts to harmful abrasives and liquids. Moreover, the enclosure of the can lifts provides a guard to prevent attendants and their apparel from accidentally contacting the moving parts of the machine. Since the can lifts are completely concealed they are not accessible for manual lubrication and it is, therefore, one object of the present invention to provide them with a self-contained oiling system.

It is another object of this invention to utilize the mechanical motion of the lifts in syruping machines for automatically lubricating the concealed moving parts of such lifts.

Another object is to provide an oiling system for lifts whereby lubricating medium is continually supplied to the uppermost bearing surfaces thereof for gravitation therethrough to assure adequate lubrication of internal moving parts of the lifts.

Other objects and advantages will become apparent in the following description in connection with the drawings in which:

Fig. 1 is a vertical section of a can lift embodying the present invention.

Fig. 2 is a vertical section of a portion of Fig. 1 taken along line 2—2 thereof.

Fig. 3 is a horizontal section of Fig. 1 taken along line 3—3 thereof.

Fig. 4 is an enlarged fragmentary bottom view of certain portions of the lift of Fig. 1 taken along line 4—4 thereof.

Fig. 5 is a fragmentary section showing a partial elevation of a cam track associated with the lift and taken along line 5—5 in Fig. 1.

Referring now to the drawing, the syruping machine partially illustrated therein is of the general type disclosed in Patent No. 1,811,908 to W. de Back, dated June 30, 1931, and comprises

10 a fixed base 1, a movable turret or carriage 2, and a can lift 3.

15 It will be understood that there are a plurality of lifts arranged in spaced relation on the carriage 2 and that the latter is preferably in the form of a turret mounted for rotation about a vertical shaft, not shown, the details of which may be had by reference to the aforementioned patent. Since all of the lifts 3 are of identical construction and operate in the same manner, only one of them is illustrated and described herein.

20 The fixed base 1 comprises a stationary casting 5 provided with a bottom wall 6 and spaced upwardly therefrom walls 7 and 8 providing an oil sump 9. This sump 9 contains a body of oil to a standing level 10, as is shown in Figs. 1 and 5. Formed on the bottom wall 6 and extending upwardly within the oil sump 9 is a cam 11 having an acclivity 12 (see Fig. 5) and provided with a similar declivity, not shown. The lower end of the lift 3 is provided with a roller 13 which rides upon the cam 11 as the turret is rotated in a horizontal plane relative to the fixed base 1. Each can lift 3 is provided with a table 14 adapted to receive a container, such as a jar or can, for alternately raising and lowering the same with respect to a filling valve associated therewith, not shown, so that the container will receive a charge of syrup from the valve in a manner well known in the art.

25 The present application is directed to an oiling system for the lift for lubricating the same automatically as the lift is raised and lowered in the course of presenting a container to the syruping valve. The lift 3 comprises a vertically disposed stationary sleeve 15 having an annular flange 16 (Fig. 2) midway its ends secured to the turret 2 by means of stud bolts 17 to dispose the sleeve in axial alignment with and above the cam 11. A portion of the lower end of the sleeve 15 extends down into the oil sump 9 and the upper portion of the sleeve extends a substantial distance above the turret 2. The sleeve 15 is provided with a lower bushing 18 and an upper bushing 19 spaced from each other to provide an annular chamber 20 within the sleeve.

30 Slidably mounted in the bushings 18 and 19 is a shaft 22 having a central bore 23. The lower extremity of the shaft 22 is bifurcated to provide depending arms 26 and 27 straddling the roller 13 which is disposed therebetween. The roller 13 is provided with a bushing 31 mounted on a spindle 32 extending between the arms 26 and 27 and

secured to the arm 27 by a set screw 36, as is shown in Fig. 1.

The spindle 32 has an axial extension 37 secured thereto by a stud bolt 38 and mounted on this extension 37 is a guide roller 39 and an auxiliary roller 40. The auxiliary roller 40 is adapted to engage an overhead cam 41 formed integrally with the side wall 7 of the fixed base 1 and associated with the cam 11, hereinbefore mentioned, to provide a cam track 42 in the casting 5. The guide roller 39 is adapted to move up and down in a vertical groove or slot 43 provided in the lower portion of the sleeve 15 and bushing 18 to prevent turning of the shaft 22 due to torque as the roller 13 travels along the cam 11.

The table 14 comprises a platform 44 having an upstanding edge 45 adapted to receive the lower bead of a can fed onto the table and for supporting the can or container in axial alignment with the filling valve, hereinbefore mentioned. The underside of the platform 44 is recessed, as is shown at 46 in Figs. 1 and 2, to receive an annular ring 47 seated in a recess 48 formed in a complementary plate 49. Within the recess 48, the complementary plate 49 is provided with a central hub portion 51 to which is welded the reduced end 52 of a rod 53. Around the hub 51, the plate 49 is provided with equally spaced holes or openings 54 and 55. The holes 55 (Fig. 1) each receive, from below, the threaded shank of a stud pin 56, the upper ends of which are secured to the plate 49 by a nut 57. The holes 54, as shown in Fig. 2, have elongated stud bolts 58 extending therethrough and into a recess 59 formed in the upper end of the shaft 22.

Each bolt 58 and stud pin 56 is surrounded by a compression spring 60 having its lower end bearing against the floor of the recess 59 and its upper end bearing against the lower face of the complementary plate 49. The stud bolts 58 are threaded into tapped holes 61 in the floor of the recess 59 and are screwed down so that the heads of the bolts 58 will normally hold the plate 49 down upon the springs 60 leaving a slight clearance between the upper end of the shaft 22 and the lower face of the plate 49.

The rod 53 extends down into the central bore 23 provided in the shaft 22 and is slidably supported therein by upper and lower bearings 62 and 63, respectively, provided in the shaft 22. The complementary plate 49 is secured to the underside of the platform 44 by stud screws 65 extending through an annular ring 66 which bears against a lateral flange 67 of a depending skirting 68. This skirting 68, as will be seen in Fig. 1, acts as a shield for the upper end of the sleeve 15 preventing juices and vegetable matter from entering the oiling system.

The shaft 22 has an eccentric bore 70 formed therein disposed in a plane corresponding diametrically to the axis of the spindle 32 and roller 13. Arranged in the eccentric bore 70 is a tubular sleeve 71 having its lower end extending through a segmental plate 72 which is threaded secured to the sleeve 71. The plate 72 is keyed to the lower portion of the sleeve 15 adjacent the roller 13, as is shown in Figs. 1 and 4, to maintain the tubular sleeve 71 stationary relative to the vertically movable shaft 22 and to dispose the lower open end of the sleeve 71 beneath the standing level 10 of oil in the sump 9.

Disposed within the lower portion of the tubular sleeve 71 is a check valve comprising a floating valve plunger 73 having a conical lower tip 74 resting upon an annular seat 75 provided by

5 a tubular plug 76 press fit into the lower end of the tubular sleeve. The eccentric bore 70 has an enlarged upper end adjacent the recess 59 provided with an inside thread to which is threaded a tubular plug 77 having an orifice 78 in its lower end. Arranged in the tubular plug 77 is a valve plunger 79 having its conical lower end 80 resting upon a seat 81 provided at the rim of the orifice 78 to provide a check valve at the upper end of the bore 70.

10 The tubular sleeve 71 and the eccentric bore 70 together with the upper and lower check valves associated therewith constitute a pump for lifting oil from the sump 9 to the recess 59 in the upper end of the shaft 22.

15 Diametrically opposite the eccentric bore 70, the shaft 22 is provided with a passage 82 extending vertically from the recess 59 to a point substantially midway between the ends of the shaft. The outer surface of the shaft 22 is provided with an annular groove 83 in the region of the upper bearing 19 and this annular groove is in communication with the passage 82 by way of a laterally disposed bore 84. At the lower end 20 of the passage 82 the shaft 22 is provided with a lateral bore 85 which communicates with the annular chamber 28. It will be noted in Fig. 1 that the upper and lower bearings 62 and 63 surrounding the rod 53 are spaced substantially from each other to provide an annular chamber 86 circumscribing the rod and that the lateral bore 84, mentioned above, communicates with the upper portion of the annular chamber 86. The lower end of the annular chamber 86 is provided 25 with a drain in the form of a diametrical bore 87 in the rod 53 communicating with an axial bore 88 extending upwardly from the lower end of the rod.

30 During operation of the lift, the turret 2 is moved in a horizontal plane relative to the stationary casting 5 causing the roller 13 to travel along the cam track 11. As the roller 13 climbs the acclivity 12 of the cam 11 (Fig. 5) the shaft 22 is lifted relative to the stationary sleeve 15 35 secured to the turret.

35 As hereinbefore pointed out, the upper end of the shaft 22 is spaced slightly from the lower end of the complementary plate 49. This spacing compensates for slight variations in the height of cans or jars fed to the table 14. In other words, 40 some containers will engage a filling valve before others and, therefore, the compression springs 60 permit yielding of the table 14 when a higher jar, disposed thereon, engages the filling valve before the lift has reached its extreme raised position.

45 Upon lifting of the shaft 22, as aforesaid, the latter and the rod 53 are elevated until the high point of the cam 11 is reached. During such elevation of the shaft 22 and table 14, the lower 50 end of the stationary sleeve 15 travels below the standing level 10 of oil in the sump 9. Consequently, since the tubular sleeve 71 is secured to the sleeve 15 and the shaft 22 is elevated relative to the sleeves, the tubular sleeve 71 and the bored portion 70 of the shaft 22 are moved telescopically 55 with respect to each other. The upper valve plunger 79 while resting upon its seat 81 is simultaneously elevated with the shaft 22 elongating the space between the plungers 79 and 73 thereby creating a vacuum in the eccentric bore 70 causing atmospheric pressure acting upon the standing level of the oil in the sump to force a quantity of oil against the lower valve plunger 73 lifting the latter from its seat 75 as the oil passes into 60 the tubular sleeve 71. The plunger 73 will then

automatically return to the seat 75 and the oil in the sleeve 71 will stand as a column well above the level of the oil in the sump as the turret continues to move the can lift horizontally relative to the stationary base 1.

The roller 13 in passing the declivity of the cam 11 is caused to descend by engagement of the roller 48 with the overhead cam 41 causing the column of oil in the sleeve 71 to press the lower valve plunger 73 down upon its seat 75 checking movement of the oil within the sleeve toward the sump. Upon descent of the shaft 22, the space between the valve plungers 79 and 73 is decreased and simultaneously therewith the upper valve plunger 79 is unseated by the air pressure above the column of oil. The air escaping from the bore 70 by way of the valve 79 passes out through the recess 59 and the space between the upper end of the shaft 22 and the complementary plate 49.

After two or three such up and down operations of the shaft 22 the volume of oil standing within the sleeve 71 will rise to a level well above the normal lower limit of the upper valve plunger 79 so that upon downward movement of the same, the plunger 79 will be lifted from its seat 81 by oil passing into the recess 59. Continued operation of the can lift and the pump associated therewith in the above stated manner assures that the recess 59 will always be supplied with oil, thus, providing an overhead reservoir of oil in the upper end of the shaft. Each time the lift begins to descend releasing a container from its engagement with the filling valve, above, the compression springs 60 assure that the shaft 22 will be spaced away from the underside of the complementary plate 49. The space between the plate 49 and shaft 22 permits air to enter the reservoir in the recess 59 to thereby prevent the oil in the oiling system from becoming air locked and to allow the oil to gravitate from the reservoir by way of the passages 82, 84, 85 toward the bearings and bushings below the reservoir.

The oil gravitates from the recess 59 into the passage 82 and by way of the lateral bores 84 and 85 into the annular groove 83 and the annular chambers 20 and 86. The uppermost bearing 62 associated with the rod 53 is lubricated direct from the reservoir. The oil flowing into the annular groove 83 lubricates the uppermost bushing 19 associated with the shaft 22 and the oil entering the annular chamber 20 lubricates the shaft 22 midway its ends and provides a constant supply of oil which works its way down between the bushing 18 and lower portion of the shaft 22. The oil dripping from the lower end of the bushing 18, incidental to dropping into the sump 9, lubricates the guide roller 33 and the roller 40 associated with the overhead cam 41.

The volume of oil supplied to the reservoir from the bore 70 is far in excess of the amount of oil required to lubricate the bushings 18, 19, 62, and 63, and, therefore, the excess oil is carried off by an overflow system by way of the inward portion of the lateral bore 84 which discharges into the annular chamber 86. As hereinbefore stated, the lower end of the chamber 86 is in communication with the drain provided by the bores 87 and 88 in the lower end of the rod 53. Consequently, the oil gravitating into the chamber 86 is in a constant state of flow and pours from the bore 88 down onto the roller 13 lubricating the latter as well as the cam track 11.

From the foregoing it is apparent that the oil in the reservoir can never rise above the upper

end of the sleeve 15 and overflow onto the exterior surfaces of the turret. Incidental to the draining of oil from the chamber 86, the lowermost bearing 63 associated with the rod 53 is kept well lubricated by whatever oil passes between the bearing 63 and rod. The oil draining from the several lubricated bushings and bearings is returned to the sump 9, thereby assuring that the standing level 10 of oil will be sufficiently high to supply each of the lifts with lubricant.

It is apparent, for the reasons stated above, that I have provided a novel self-contained lubricating system for assuring automatic lubrication of all of the moving parts of a continually reciprocating lift during its operation. The movable parts of such lift can, therefore, be concealed and shielded to prevent contamination of the pack, and at the same time is protected against damage by abrasives and foreign material.

While the foregoing structure has been described specifically, it will be apparent to those skilled in the art that the same may be altered or modified for various applications in conjunction with reciprocating mechanism, and, consequently, need not be restricted to the specific structure shown herein. I, therefore, desire to avail myself of all modifications and alterations coming within the purview of the appended claims.

What I claim as new and desire to protect by Letters Patent is:

1. An oiling system for a lift comprising a stationary base providing an oil sump and having a lift operating track, a carriage movable horizontally relative to said base, a shaft slidably mounted on said carriage and operatively connected with said track for reciprocation upon movement of said carriage, said shaft having a stand pipe associated therewith extending upwardly from said sump parallel to said shaft, a check valve in the lower end of said stand pipe disposed beneath the standing level of oil in said sump, said shaft having telescopic relation with respect to said stand pipe, a check valve in the head of said shaft operatively associated with said stand pipe, means for moving said carriage relative to said base for alternately raising and lowering said shaft relative to said carriage and stand pipe for lifting oil from said sump to the head of said shaft, and means in the head of said shaft communicative with the check valve and the bearing surface of said shaft for directing oil to said bearing surface to lubricate the same.

2. An oiling system for a lift comprising a base provided with an oil sump having a standing level of oil therein, a turret arranged above said base for relative movement with respect thereto, said turret having a sleeve extending downwardly toward said sump, a stand pipe having a valve in its lower end disposed below the standing level of oil in said sump, a shaft arranged in said sleeve and having telescopic relation with respect to said stand pipe, said shaft having a chamber in its head communicating with said stand pipe, a check valve between the chamber and stand pipe, said shaft having a port communicating said chamber with the space between said sleeve and shaft, a track on said base, and means on said shaft disposed in said track for alternately raising and lowering said shaft during movement of said turret relative to said base whereby oil will be lifted from said sump to said chamber for lubricating the shaft and sleeve and for returning

the oil to said sump by way of the space between said sleeve and shaft.

3. An oiling system for a reciprocating mechanism comprising a base provided with an oil sump having a standing level of oil therein, a turret arranged above said base for relative movement with respect thereto, said turret having a sleeve extending downwardly toward said sump, a stand pipe having a check valve in its lower end disposed below the standing level of oil in said sump, a shaft arranged in said sleeve and having telescopic relation with respect to said stand pipe, said shaft having a chamber in its head communicating with said stand pipe, a check valve between the chamber and stand pipe, said shaft having ports communicating said chamber with the space between said sleeve and shaft, means on said base and shaft operatively related for alternately raising and lowering said shaft upon movement of said turret whereby oil will be lifted from said sump to said chamber for lubricating the shaft and sleeve, and an overflow bypass in said shaft for draining excess oil from said chamber into said sump.

4. A can lift for a syruping machine comprising a base providing an oil sump and having a cam track associated therewith, a turret arranged above said base for relative movement with respect thereto, said turret having a bearing, a shaft in said bearing, means on said shaft operatively engaging said cam track, a tube supported for movement with said turret and telescopically associated with a bore provided in said shaft and having its lower end extending into said oil sump, a check valve at the base of said tube, said shaft having a reservoir communicating with the bore above said tube, a check valve intermediate said bore and reservoir, said shaft having a passage interconnecting said reservoir with the bearing surface of said sleeve and shaft, and means for moving said turret horizontally with respect to said base for causing up and down movement of said shaft relative to said cam track and bearing, whereby to draw oil from said sump into said reservoir for gravitation between said bearing and shaft.

5. A can lift for a syruping machine comprising a base providing an oil sump and having a cam track associated therewith, a turret arranged above said base for relative movement with respect thereto, said turret having a bearing, a shaft in said bearing, means on said shaft operatively engaging said cam track, a tube supported for movement with said turret and telescopically associated with a bore provided in said shaft and having its lower end extending into said oil sump, a check valve at the base of said tube, said shaft having a reservoir communicating with the bore above said tube, a check valve intermediate said bore and reservoir, said shaft having a passage interconnecting said reservoir with the bearing surface of said sleeve and shaft, means for moving said turret horizontally with respect to said base for causing up and down movement of said shaft relative to said cam track and bearing, whereby oil is translated from said sump into said reservoir for gravitation between said bearing and shaft, and overflow means associated with said reservoir for returning excess oil from the latter to said sump.

6. An oiling system for a can lift comprising a base provided with an oil sump and having a cam track, a carriage movable relative to the base provided with a bearing, a shaft mounted in

the bearing operatively associated with the cam track for effecting reciprocating movement of said shaft as the carriage is moved relative to the base, a rod slidably mounted in the shaft carrying a table for receiving a container, resilient means between the shaft and table for permitting yielding movement of the latter, said shaft having a recessed upper end encircling the rod, a passage formed in the shaft between the recess and the periphery of said shaft, a fluid pump operable by the shaft having an inlet submerged in the oil in the sump and an outlet communicating with the recessed upper end of said shaft, and means for moving the carriage relative to the base for effecting reciprocation of said shaft and for operating the pump whereby the latter will supply oil to the recessed upper end of said shaft for gravitation toward the sump by way of the space between the bearing and shaft and the shaft and rod.

7. An oiling system for a cam lift comprising a base provided with an oil sump and having a cam track, a carriage movable relative to the base provided with a bearing, a shaft mounted in the bearing operatively associated with the cam track for effecting reciprocating movement of said shaft as the carriage is moved relative to the base, a rod slidably mounted in the shaft carrying a table for receiving a container, resilient means between the shaft and table for permitting yielding movement of the latter, said shaft having a recessed upper end encircling the rod, a passage formed in the shaft between the recess and the periphery of said shaft, a fluid pump operable by the shaft having an inlet submerged in the oil in the sump and an outlet communicating with the recessed upper end of said shaft, means for moving the carriage relative to the base for effecting reciprocation of said shaft and for operating the pump whereby the latter will supply oil to the recessed upper end of said shaft for gravitation toward the sump by way of the space between the bearing and shaft and the shaft and rod, and overflow means between the recessed upper end of the shaft and the lower end of the rod for returning excess oil from the recess to the sump.

8. An oiling system for a cam lift comprising a base having an oil sump and a cam track, a carriage movable relative to said base provided with a bearing, a shaft mounted in the bearing operatively associated with the cam track for effecting reciprocating movement of said shaft as the carriage is moved relative to the base, a reservoir in the upper end of said shaft communicating with the bearing in said carriage, a fluid pump operable by said shaft having an inlet submerged in the oil sump and an outlet communicating with said reservoir, means for moving the carriage relative to the base for effecting reciprocation of said shaft and for operating the pump whereby the latter will supply oil to the reservoir in said shaft for gravitation toward the sump by way of the space between the bearing and shaft.
